UNITED STATES PATENT OFFICE

2,590,538

INKING MECHANISM FOR PRINTING MACHINES

William F. Huck, Forest Hills, N. Y., assignor to
 R. Hoe & Co., Inc., New York, N. Y., a corporation of New York

Application May 30, 1945, Serial No. 596,625

3 Claims. (Cl. 137—78)

1

This invention relates to rotogravure printing machines and more particularly to inking mechanism for such machines in which the ink used contains a highly volatile solvent or thinner and it is desirable to maintain the proper proportion of solvent in the ink, in order to produce high quality printing.

The ink solvent or diluent in the inking system of certain printing machines constantly evaporates and thus requires replacement at frequent intervals, to maintain the ink solvent and other ingredients of the ink in their proper proportions. As constant attention of the operator is required to maintain the proper ink mixture when the replacement of solvent is done manually, and at such intervals that no variation in the printing will be noticeable, it is desirable that replacement of ink solvent be done automatically, and that the mechanism for doing it be as critical to changes in the mixture as is practical.

An object of this invention is to provide an improved mechanism for automatically accomplishing the replacement of solvent evaporated from ink being used in a printing machine.

A more specific object is to provide, in an inking mechanism for a rotogravure printing machine, means responsive to variations in solvent content of the printing ink, to automatically control the addition of ink solvent as required to replace solvent lost by evaporation and maintain the proper proportion of solvent in the ink.

With the foregoing and other objects in view, which will appear as the description proceeds, the invention resides in the combination and arrangement of parts and in the details of construction hereinafter shown, described and claimed.

The drawing illustrates the combination and arrangement of parts and details of construction of an inking mechanism for a rotary intaglio printing machine embodying the features and principles of this invention.

Referring now to the drawing, the reference numeral 11 denotes a web passing between a printing cylinder 12 and an impression cylinder 13. The printing cylinder 12 rotates in an ink fountain 14 in which a supply of ink 15 is maintained by an ink pump 16. The ink pump 16 is connected to a reservoir 17 from which it pumps ink to the fountain 14 through a suitable pipe 18. The desired level of ink 15 is maintained in the fountain 14 by means of an overflow pipe 19 which leads back from the fountain 14 to the reservoir 17. The ink 15 in the system is composed of a mixture of suitable materials and ink solvent in

2

proper proportions to produce high quality printing on the web 11 by the printing cylinder 12.

A mixing chamber 21 is disposed in the system between the reservoir 17 and the pump 16 and a needle valve 22 is disposed in the system between the pump 16 and the pipe 18. The needle valve 22 is for the purpose of providing a manually adjustable restriction to the flow of ink mixture from the pump 16 to the pipe 18 and to thereby create a pressure on the pump side of the valve 22. A tube 23 is connected to the system between the pump 16 and the needle valve 22 and leads to a pressure indicator, or gauge 24 of well-known construction having a shaft 37 carrying an indicating pointer 25 that is rotated in relation to a dial 26 when the pressure in the tube 23 varies.

A tube 27 leads from a solvent tank 28 to a valve 29 arranged to be controlled and operated by means of an electrical circuit, herein shown in simplified form as it forms no part of the invention. A tube 32 leads from the valve 29 to and into the mixing chamber 21. An electrical conductor 33 leads from a line terminal L2 to one terminal of a solenoid 31, and an electrical conductor 34 leads from the other terminal of the solenoid to a plate 35 located on but insulated from the dial 26. A contact pin 36 is adjustable along the plate 35 and may be positioned manually at the point on the dial at which it is desired to operate the valve 29. Thus when the pointer 25 reaches the contact pin 36, a circuit is made through the plate 35, pin 36, pointer 25, shaft 37 and conductor 38 to a line wire L1 energizing the solenoid 31 to open the valve 29 and allow solvent to flow from the tank 28 to the mixing chamber 21, to be mixed with the ink mixture being pumped from the reservoir 17 into the pipe 18. The valve 29 has a handle 30 that may be adjusted to vary the rate of flow of solvent from the tank 28 when the valve is opened by the solenoid. Adjusting the pin 36 along the dial 26 in the direction of increasing pressure will keep the solenoid 31 from being energized until the liquid discharged from the pump 16 has attained a relatively high viscosity or consistency, whereas adjusting the pin 36 in the reverse direction allows the solenoid 31 to operate when the liquid is at a relatively low viscosity.

Addition of solvent into the ink flowing from the reservoir 17 decreases the viscosity of the mixture whereby a greater flow will pass through the needle valve 22 and the fluid pressure at the inlet side of the valve 22 will be reduced and so indicated by the gauge 24. When the desired

proportion of solvent in the ink mixture has been obtained the pointer 25 will be moved out of contact with the contact pin 36 de-energizing the solenoid and allowing the valve 29 to close, thus shutting off the flow of solvent to the mixing chamber 21. Gradual evaporation of the solvent in the ink mixture as it is being used will increase the viscosity of the mixture and gradually less ink mixture will pass through the restricted opening in the needle valve 22 whereby a gradual increase in pressure in the tube 23 and in the gauge 24 will result. When this pressure reaches a pre-determined amount, the pointer 25 will contact the contact pin 36 to again energize the solenoid and open the valve 29. By adjusting the needle valve 22, variations in the viscosity of the ink mixture may be made. Manually adjusting the needle valve 22 to decrease the amount of liquid that can flow therethrough, increases the pressure on the gauge 24 and thus causes the solenoid 31 to open the valve 29 when the liquid is at a relatively low viscosity, whereas adjustment of the needle valve to increase the flow will decrease the pressure on the gauge 24 and require a relatively high viscosity in the liquid before the valve 29 will open. After proper adjustment of the needle valve 22 and of the pin 36, the mechanism of this invention will automatically maintain the proper and desired proportion of solvent and ink in the ink mixture to insure high quality printing.

It will be understood that the invention may be embodied in other specific forms without departing from the spirit or essential attributes thereof, and it is therefore desired that the present embodiment be considered in all respects as illustrative and not restrictive, reference being made to the claims rather than to the foregoing description to indicate the scope of the invention.

What I claim is:

1. An ink circulating system for a printing machine including an ink fountain, an ink reservoir, a suitably driven pump having a first connection through which it receives ink from the reservoir

and a second connection through which it discharges ink to the fountain, there being a third connection through which ink from the fountain is returned to the reservoir; the combination therewith of means for determining the consistency of the circulating ink, including a restriction in the said second connection to raise the fluid pressure at the discharge side of the pump, and means to indicate the fluid pressure between the outlet of the pump and the restriction.

5 2. The combination according to claim 1 in which the said first connection includes a mixing chamber into which solvent is admitted to be mixed with the ink passing to the pump.

10 3. The combination according to claim 1 in which the said restricting means consists of a valve for throttling the flow of ink to thereby regulate the fluid pressure where it is discharged from the pump.

15 WILLIAM F. HUCK.
